CLAIM

The ornamental design for a reflector for an infrared radiation unit, as shown and described.

DESCRIPTION

FIG. 1 is an end view of a reflector for infrared radiation unit showing my new design;

FIG. 2 is a perspective view thereof;

FIG. 3 is a top plan view thereof;

FIG. 4 is a side elevational view thereof, the opposite side being identical;

FIG. 5 is a bottom plan view thereof;

FIG. 6 is an end view of a second embodiment of FIG. 1;

FIG. 7 is a perspective view of FIG. 6;

FIG. 8 is an end view of a third embodiment of FIG. 1;

FIG. 9 is a perspective view of FIG. 8;

FIG. 10 is an end view of a fourth embodiment of FIG. 1;

FIG. 11 is a perspective view of FIG. 10;

FIG. 12 is a side elevational view of FIG. 10, the opposite side being identical;

FIG. 13 is a bottom plan view of FIG. 10;

FIG. 14 is a top plan view of FIG. 10;

FIG. 15 is a top plan view of FIG. 6;

FIG. 16 is a bottom plan view of FIG. 6.

The sections are shown broken away to illustrate indeterminate length;

The article is of infinite length.

FIG. 9

FIG. 7

FIG. 2
